(57) **CLAIM**

The ornamental design for an injection needle shield puller, as shown and described.

DESCRIPTION

FIG. 1 is a top, front and right side perspective view of an injection needle shield puller, in accordance with our new design;

FIG. 2 is a front elevational view thereof, a rear elevational view being identical thereto;

FIG. 3 is a right side elevational view thereof, a left side elevational view being identical thereto;

FIG. 4 is a top plan view thereof; and,

FIG. 5 is a bottom plan view thereof.

The broken lines in the figures are for the purpose of showing environmental structure and form no part of the claimed design.

1 Claim, 5 Drawing Sheets---
